CLAIM

The ornamental design for an anti-theft box, as shown and described.

DESCRIPTION

FIG. 1 is a top perspective view of an anti-theft box showing the new design;

FIG. 2 is a bottom perspective view of the anti-theft box;

FIG. 3 is a front view of the anti-theft box;

FIG. 4 is a back view of the anti-theft box;

FIG. 5 is a right side view of the anti-theft box;

FIG. 6 is a left side view of the anti-theft box;

FIG. 7 is a top view of the anti-theft box; and,

FIG. 8 is a bottom view of the anti-theft box.

The broken lines illustrate portions of the anti-theft box that form no part of the claimed design.

1 Claim, 7 Drawing Sheets
